UNITED STATES PATENT OFFICE.

JOHN KOPP, OF CINCINNATI, OHIO.

BRIDGE FOR VIOLINS.

SPECIFICATION forming part of Letters Patent No. 388,883, dated September 4, 1888.

Application filed January 26, 1888. Serial No. 262,029. (No model.)

To all whom it may concern:

Be it known that I, JOHN KOPP, a citizen of the United States, and a resident of Cincinnati, in the county of Hamilton and State of Ohio, 5 have invented certain new and useful Improvements in Bridges for Violins, of which the following is a specification.

The several features of my invention and the advantages arising from their use, conjointly 10 or otherwise, will be apparent from the following description.

In the accompanying drawings, forming part 15 of this specification, Figure 1 is a side elevation of a violin-bridge embodying my invention. Fig. 2 is an edge elevation of the same. Fig. 3 is a cross-section of a violin, showing the bridge in elevation and in position. Fig. 4 is a view of one of the pieces which when in use are attached to the bottom of the bridge.

20 The invention is equally applicable to bridges for violins, violas, violoncellos, and bass-viols.

The bridge ordinarily employed has two disadvantages. The bridge participates in the vibrations of the strings and the body, and to 25 have the instrument perfect, the bridge must vibrate in exact unison with the body of the instrument—in fact, should fit so closely as to be practically part of the body. It is exceedingly difficult to accurately fit a bridge to the 30 belly of the instrument, and the slightest inaccuracy in the fit impairs the delicacy of the instrument's tone, giving rise to secondary interfering vibrations. Another disadvantage 35 arises from the fact that the bridge is made of hard wood, and whenever it falls down, the surface of the instrument is slightly abraded

by the act of falling and the subsequent act of replacement. In time this repeated replacing of the bridge causes slight holes to be formed 40 in the top of the instrument, impairing the clearness of its tones. In avoiding these difficulties I have provided the feet of the bridge A with a slight thickness of a substance (marked *a* in the drawings) which is softer 45 than the hard wood of which the bridge is made, soft enough, in fact, to make a perfect joint between the bridge and the belly, as B, of the instrument, and to maintain the perfection of the joint during vibrations produced in playing 50 the instrument, but not so soft as to interfere with transmission of vibrations between the body and the strings. The substance employed is bark, and may be described in this connection as sonorous, but relatively more 55 porous than the bridge proper or the body.

Only those descriptions of bark which are quite elastic and porous and of which the fibers constituting the wood are capable of vibration are to be used. For these purposes cork is 60 not fit, neither is rubber, as both cork and rubber are too dense and damp or deaden and retard the vibrations of the violin and impair the tones.

What I claim as new, and desire to secure 65 by Letters Patent, is as follows:

The combination of a violin-bridge and foot-pieces *a* and a light elastic porous bark whose fibers are capable of vibration, substantially as and for the purposes specified.

JOHN KOPP.
